UNITED STATES PATENT OFFICE.

ENOS BLANCHARD PETRIE, OF BROOKLYN, NEW YORK.

TURBINE.

1,403,103.

Specification of Letters Patent. Patented Jan. 10, 1922.

Application filed October 18, 1920. Serial No. 417,760.

To all whom it may concern:

Be it known that I, ENOS BLANCHARD PETRIE, a citizen of the United States of America, residing at Brooklyn, State of New York, United States of America, have 5 invented certain new and useful Improvements in Turbines, of which the following is a specification.

This invention relates to turbines, and 10 has for its object to produce an engine of this type which will be useful in all fields of industry where engines are employed.

The main object of the present invention is to produce a turbine in which the direct 15 passage of the motive fluid from the inlet ports to the exhaust port will be prevented in an effective manner and by the employment of simple and easily operable means.

The engine of the present invention further 20 is designed with a view to reducing the initial cost of production and of subsequent upkeep, and, for a given size of engine, to produce more power with a given quantity of fuel than has heretofore been obtained. The present engine is therefore 25 characterized by simplicity of construction and the reduction to a minimum of losses due to friction.

The turbine according to this invention, 30 in its broadest aspect, comprises a casing, a rotor within the casing keyed to the shaft to be driven, a plurality of pockets formed about the circumference of the rotor, an enlarged head on the casing, inlet ports in said head for the admission of motive fluid to the rotor, valves controlling said ports, means for conducting motive fluid to said ports, an exhaust conduit in said head, adjustable abutments between said inlet ports 35 and the exhaust conduit, a clearance space between the outer extremities of the partitions between the pockets and the inside of the casing, fixed abutments on the head extending into said clearance space between 40 each inlet port and adjustable abutment and each adjustable abutment and the exhaust conduit respectively, the latter extensions being narrower than the width of a pocket, the former being slotted to permit motive 45 fluid in the clearance space to pass thereby, and the adjustable abutments being wider than the width of a pocket in the rotor.

A further object is to produce a compact 50 rotary multistage engine, comprising preferably a high-pressure and a low-pressure engine arranged to operate in unison.

In order that the invention may be readily understood two examples of engines constructed in accordance therewith will now be described with reference to the accompanying drawings in which:—

Figure 1 is a longitudinal view, partly 65 in section, of an engine designed for high-pressure work constructed according to the present invention.

Figure 2 is a transverse section of the engine shown in Figure 1.

Figure 3 is a diagrammatic view showing a high-pressure engine arranged in conjunction with a low-pressure engine, the former 70 discharging its exhaust motive fluid into the latter.

Figure 4 is an end view of a high pressure engine and a low pressure engine constructed and arranged according to this invention.

Figure 5 is a sectional view, at a right angle to Figure 4, of the engine shown in the latter figure.

In the several figures of the drawings, 80 like parts are indicated by similar reference numerals.

Referring more particularly to Figures 1 and 2, 1 is the bed plate, 2 the casing of the engine provided at the upper part with an enlarged head 3 to accommodate the inlet and exhaust valves and other mechanism hereinafter to be more fully described, and 4 are the end plates or cylinder heads of the casing 2 which may be conveniently secured 85 to said casing by means of bolts 5. The end plates are preferably formed in two parts as shown to facilitate their removal.

6 is the engine shaft carried in bearings 7 secured to the bed plate 1 of the engine 90 by means of bolts 8. The bed plate extends far enough aft, that is to say, to the left of Figure 1, to accommodate the usual driving collar (not shown).

Keyed to the shaft 6 by a key 9 is a rotor 100 10 comprising a sleeve 11 encircling the shaft, arms 12 extending radially therefrom and a ring 13, in the outer face of which are formed a series of pockets 14 extending circumferentially around the same, each 105 of said pockets 14 being separated from those next adjacent thereto by partitions or walls 15. Preferably the pockets are, in transverse section, of the shape shown in Figure 2, that is to say, they are defined by 110 two adjacent partitions 15 and have sloping bottoms 16 making the pockets deeper

adjacent one partition 15 than the other partition.

The pockets 14 extend longitudinally practically the whole length of the ring 13 as will best be seen from Figure 1, the material of the ring being left as shown at 17 to form the end walls of the pockets.

The sleeve 11, arms 12 and ring 13 constituting the rotor 10 are all formed in one piece and are designed to produce a comparatively hollow structure thus avoiding the employment of waste metal and giving a light and compact rotating member.

Between the engine casing 2 and the outer circumference of the ring 13 is a clearance space 18.

19 and 20 are the inlet conduits for the motive fluid, each of which are provided with lateral extensions 21 which open into 20 inlet ports 22 formed in the head 3 of the casing 2. The ports 22 are respectively provided with valves 23, 24 for controlling the admission of the motive fluid, and said ports and valves extend longitudinally of the engine for a distance equal to, or practically so, the length of the pockets 14. The sides of the head 3 are closed by plates 25 secured to the head by bolts 26.

27 is the exhaust conduit. Between each 30 of the inlet ports 22 and the exhaust conduits 27 are arranged in suitable openings formed in the head 3 adjustable abutments 28, 29 each provided with a base 30 curved to correspond to the rotor periphery, a 35 screwed stem 31 and a head 32, which latter extends above the engine casing 2 to permit of operation by any suitable means. The base 30 of each adjustable abutment is adapted to contact with the outer circumference of the ring 13.

The operation of the engine may be described as follows:

Assuming that the engine is to rotate in the direction of the arrow shown in Figure 45 2, the abutment 28 is closed or lowered until its base 30 contacts lightly with the periphery of the ring 13 as shown in said figure, and valve 24 is closed, whilst the valve 23 is opened and abutment 29 is raised. The motive fluid will then pass through the pipe 19 and lateral extensions thereof at the right hand side of the figure into the inlet port 22 at that side of the figure, thence past the open valve 23 and its energy will be impressed on the rotor 10 by reason of its contact with the partitions 15; and the rotor 10, and through it the shaft 6, will be revolved in the direction of the arrow in Figure 2. Part of the motive fluid thus admitted will travel around the clearance space 18 between the casing 2 and the ring 13 and such part will constantly impress its energy on the partitions 15 and thus a constant or continual driving force, in addition to the 60 initial impulse given to them on coming into

contact with the incoming fluid, will be exerted on all the pockets in action until they reach the conduit 27 when the motive fluid is exhausted therefrom into said conduit 27 and thence passes to a condenser, or into a low-pressure engine, which latter arrangement will be hereinafter described in connection with Figures 3, 4 and 5.

In order to run the engine in the reverse direction the valve 23 is closed, the abutment 29 is lowered or closed, the valve 24 opened and the abutment 28 raised. The action will then be exactly as above described, except, of course, that the rotor 10 and with it the shaft 6, will revolve in the opposite direction. If desired the valve 23 and the abutment 29 may be so interconnected that by the operation of a single lever or other operating means they may both be opened or closed by a single movement of said lever or other means. The same arrangement may be effected in connection with valve 24 and abutment 28.

Between the valve 23 and the adjustable abutment 28 the head 3 of the casing is extended into the clearance space 18 forming a fixed abutment as shown at 33, and between the valve 24 and the adjustable abutment 29 the head 3 is similarly extended as shown at 34 forming a similar fixed abutment. In order to permit the motive fluid in the clearance space 18 to pass said fixed abutments 33, 34, the latter are provided with a series of slots indicated by the dotted line in Figure 2, forming a comb-like structure.

Again, between the exhaust conduit 27 and the adjustable abutments 28, 29 respectively are further fixed abutments 35, 36 extending into the clearance space 18. It will be understood that the fixed abutments 33, 34, 35 and 36 are not extended to such an extent that they will contact with the periphery of the partitions 15, but the clearance is made as small as is compatible with the practical working of the engine.

Immediately after a partition 15 passes the abutments 35 or 36, as the case may be, the fluid in the pocket immediately following said partition will be exhausted into the conduit 27, that is to say, in Figure 2, the pocket 14^a is about to exhaust. The width of the abutments 35, 36 is less than the width of a pocket but the opening below the open adjustable abutment is greater than the width of a pocket so as to permit the motive fluid in the clearance space 18 above the pockets about to exhaust to be drawn out into the exhaust together with the fluid exhausting from those pockets.

The purpose of the adjustable abutments 28, 29 is to ensure the incoming fluid acting on the partitions in one direction only, that is to say, if the rotor is to revolve in the direction of the arrow in Figure 2, the

motive fluid entering past the open valve 23 must be controlled to exert its energy in the direction of the arrow only. In order therefore to prevent any of the fluid acting on the partitions in the opposite direction by escaping to the left of Figure 2, the abutment 28 is closed down into the clearance space 18 when said valve 23 is opened. When closed the bases 30 of the abutments 28, 29 close the open ends of the pockets 14 and prevent the motive fluid entering thereinto.

The adjustable abutments 28, 29 are constructed to act as a finely adjustable packing between inlet and exhaust.

To prevent the escape of fluid from the ends of the pockets, that is to say, past the end walls 17, the said walls are each formed with an integral circular flange 37 and this flange acting in conjunction with a ring 38 of any suitable packing material forms a lock past which it is impossible for the fluid to escape.

It is to be observed that between the casing 2 and the flange 37 is a clearance 39 to allow for slight longitudinal movements in the shaft 6 and the rotor 10 with respect to the casing 2. Such movements will be reduced to a minimum, however, by reason of the fact that the bed plate 1 and the casing 2 are cast integral and that the bearings 7 for the shaft 6 and the usual driving collar are bolted or otherwise rigidly connected to the bed plate. Should any such slight longitudinal variation take place it can readily be indicated by marking the shaft in the well-known manner and correcting the variation upon observance.

Coming now to Figures 3, 4 and 5, the first figure shows diagrammatically a high-pressure engine A and a low-pressure engine B arranged side by side on the shaft 6, the first-mentioned engine supplying its exhaust fluid to the low-pressure engine by means of a connection C.

If desired a second high-pressure engine could be arranged on the shaft 6 on the side opposite to that at which engine A is placed, and with such an arrangement both high-pressure engines would be arranged to supply their exhaust fluid to the low-pressure engine B.

Figures 4 and 5 show the development of the arrangement shown in Figure 3.

In a general way the construction of this multiple engine is identical with that of the high-pressure engine above described. The exhaust motive fluid from the conduit 27 is, however, led to a valve chamber 50 in which is arranged the two-way valve 51. From this chamber extend two conduits 52, 53 which respectively lead the motive fluid to two inlet ports similar to those described above, numbered 22. The valve 51 is operable by the lever 54 but any other suitable

means may be provided for the same purpose. 55 is the exhaust conduit of this low-pressure engine.

When the valve is in the position shown in dotted lines in Figure 4 the motive fluid will enter the low-pressure machine by way of the conduit 52 and the engine will be driven in the forward direction. When it is desired to reverse the direction of rotation, the valve 51 is operated to close the conduit 52 and open the conduit 53.

The casing 2 for the multi-stage engine just described is preferably cast in one piece as shown in Figure 5.

A high-pressure engine constructed according to this invention having, say, an eight inch cylinder with a twenty-four inch stroke will work in unison and very efficiently with a low-pressure engine having an eighteen inch cylinder and a fifty-four inch stroke.

Where the rotor is of considerable length in a longitudinal direction it is advisable, in order to ensure that the adjustable abutments 28, 29 move freely and evenly on the opening or closing of said valves, two or more dolphin pins 56, 57 (Figure 5) may be provided at suitable distances apart to effect this object.

It will be understood that where the hereinbefore described engine is required to operate in one direction only, the inlet pipe 20, inlet port 22 at the left hand side of Figure 2, valve 24 and adjustable abutment 29 would be suppressed.

What I claim and desire to secure by Letters Patent is:—

1. A rotary engine comprising a casing, a rotor within the casing keyed to the shaft to be driven, a plurality of pockets formed in the circumference of the rotor, an enlarged head on the casing, inlet ports in said head for the admission of motive fluid to the rotor, valves controlling said ports, means for conducting motive fluid to said ports, an exhaust conduit in said head, adjustable abutments between said inlet ports and the exhaust conduit, a clearance space between the outer extremities of the partitions between the pockets and the inside of the casing, fixed abutments on the head extending into said clearance space between each inlet port and adjustable abutment and each adjustable abutment and the exhaust conduit respectively, the latter extensions being narrower than the width of a pocket, the former being slotted to permit motive fluid in the clearance space to pass thereby, and the adjustable abutments being wider than the width of a pocket in the rotor.

2. A turbine comprising a casing, a bed plate formed integral with the casing, a driving collar and bearings carried by and secured to the bed plate, a shaft to be driven mounted in said bearings, a rotor within the

casing keyed to said shaft, a plurality of pockets formed in the circumference of the rotor, an enlarged head on the casing, inlet ports in said head for the admission of motive fluid to the rotor, valves controlling said ports, means for conducting motive fluid to said ports, an exhaust conduit in said head, adjustable abutments between said inlet ports and the exhaust conduit, a clearance space 5 between the outer extremities of the partitions between the pockets and the inside of the casing, fixed abutments on the head extending into said clearance space between each inlet port and adjustable abutment and each adjustable abutment and the exhaust conduit respectively, the latter extensions being narrower than the width of a pocket, the former being slotted to permit motive fluid in the clearance space to pass thereby, and the adjustable abutments being wider than the width of a pocket in the rotor.

10 between the outer extremities of the partitions between the pockets and the inside of the casing, fixed abutments on the head extending into said clearance space between each inlet port and adjustable abutment and each adjustable abutment and the exhaust conduit respectively, the latter extensions being narrower than the width of a pocket, the former being slotted to permit motive fluid in the clearance space to pass thereby, and the adjustable abutments being wider than the width of a pocket in the rotor.

15 the adjustable abutments being wider than the width of a pocket in the rotor.

3. A turbine comprising a casing, a shaft to be driven, a sleeve keyed to the shaft, arms extending radially from the sleeve, a ring at the outer ends of the arms, a plurality of pockets formed in the circumference of the ring, an enlarged head on the casing, inlet ports in said head for the admission of motive fluid to the rotor, valves controlling said ports, means for conducting motive fluid to said ports, an exhaust conduit in said head, adjustable abutments between said inlet ports and the exhaust conduit, a clearance space between the outer extremities of the partitions between the pockets and the inside of the casing, fixed abutments on the head extending into said clearance space between each inlet port and adjustable abutment and each adjustable abutment and the exhaust conduit respectively, the latter extensions being narrower than the width of a pocket, the former being slotted to permit motive fluid in the clearance space to pass thereby, and the adjustable abutments being wider than the width of a pocket in the rotor.

20 the adjustable abutments being wider than the width of a pocket in the rotor.

4. A turbine comprising a casing, a shaft to be driven, a sleeve keyed to the shaft, arms extending radially from the sleeve, a ring at the outer ends of the arms, a plurality of pockets formed in the circumference of the ring, defined in a transverse direction by partitions, and in a longitudinal direction by the upstanding ends of the ring, an enlarged head on the casing, inlet ports in said head for the admission of motive fluid to the rotor, valves controlling said ports, means for conducting motive fluid to said ports, an exhaust conduit in said head, adjustable abutments between said inlet ports and the exhaust conduit, a clearance space between the outer extremities of the partitions between the pockets and the inside of the casing, fixed abutments on the head extending into said clearance space between each inlet port and adjustable abutment and each adjustable abutment and the exhaust conduit respectively, the latter extensions being narrower than the width of a pocket, the former being slotted to permit motive fluid in the clearance space to pass thereby, and the adjustable abutments being wider than the width of a pocket in the rotor.

25 the adjustable abutments being wider than the width of a pocket in the rotor.

tween each inlet port and adjustable abutment and each adjustable abutment and the exhaust conduit respectively, the latter extensions being narrower than the width of a pocket, the former being slotted to permit motive fluid in the clearance space to pass thereby, and the adjustable abutments being wider than the width of a pocket in the rotor.

5. A multi-stage turbine comprising a high-pressure engine and a low-pressure engine, each including a rotor keyed to the shaft to be driven and enclosed within a casing, a plurality of pockets formed about the circumference of the rotor, an enlarged head on the casing, inlet ports in said head, an exhaust conduit in said head, adjustable abutments between said inlet ports and the exhaust conduit, a clearance space between the outer extremities of the partitions between the pockets and the inside of the casing, fixed abutments on the head extending into said clearance space between each inlet port and adjustable abutment and each adjustable abutment and the exhaust conduit respectively, the latter extensions being narrower than the width of a pocket, the former being slotted to permit motive fluid in the clearance space to pass thereby, and the adjustable abutments being wider than the width of a pocket in the rotor; valves controlling the inlet ports of the high-pressure engine, a valve chamber connected to the exhaust conduit of said engine, a valve in said chamber, and two conduits leading from said chamber to the respective inlet ports of the low-pressure engine, said latter valve being arranged to open one of said conduits and close the other of said conduits, for the purpose specified.

6. A turbine comprising a casing, a shaft to be driven, a sleeve keyed to the shaft, arms extending radially from the sleeve, a ring at the outer ends of the arms, a plurality of pockets formed in the circumference of the ring, defined in a transverse direction by partitions, and in a longitudinal direction by the upstanding ends of the ring, an integral circular flange formed on the outside of each of said upstanding ends, a packing ring interposed between each of said flanges and the corresponding end plate of the casing, an enlarged head on the casing, inlet ports in said head for the admission of motive fluid to the rotor, valves controlling said ports, means for conducting motive fluid to said ports, an exhaust conduit in said head, adjustable abutments between said inlet ports and the exhaust conduit, a clearance space between the outer extremities of the partitions between the pockets and the inside of the casing, fixed abutments on the head extending into said clearance space between each inlet port and adjustable abutment and each adjustable abutment and the exhaust conduit respectively, the latter extensions being narrower than the width of a pocket, the former being slotted to permit motive fluid in the clearance space to pass thereby, and the adjustable abutments being wider than the width of a pocket in the rotor.

105 the adjustable abutments being wider than the width of a pocket in the rotor.

the exhaust conduit respectively, the latter extensions being narrower than the width of a pocket, the former being slotted to permit motive fluid in the clearance space to 5 pass thereby, and the adjustable abutments being wider than the width of a pocket in the rotor.

In testimony whereof I affix my signature in the presence of two witnesses.

ENOS BLANCHARD PETRIE.
